UNITED STATES PATENT OFFICE.

FRANK DENTLER, OF PARKVILLE, MICHIGAN.

CONVEYER AND ELEVATOR FOR THRESHING-MACHINES.

SPECIFICATION forming part of Letters Patent No. 611,197, dated September 20, 1898.

Application filed December 24, 1897. Serial No. 663,305. (No model.)

To all whom it may concern:

Be it known that I, FRANK DENTLER, a citizen of the United States, residing at Parkville, in the county of St. Joseph and State of Michigan, have invented a new and useful 5 Conveyer and Elevator for Threshing-Machines, of which the following is a specification.

This invention relates to improvements in 10 conveyers and elevators for threshing-machines; and the object that I have in view is to provide an improved mechanism which occupies a compact relation to the threshing-machine to receive the cleaned grain directly 15 from the shoe thereof and deliver such grain to a measuring and bagging mechanism.

A further object is to improve the conveying and elevating mechanism with a view to taking up the slack in the endless flight- 20 chains and to obviate the liability of straw, chaff, and refuse from being carried up to the sprocket-wheels and becoming entangled therewith.

A further object is to provide an improved 25 construction in which the grain measuring and bagging mechanism may be used at the pleasure of the attendant on either side of the threshing-machine, to which end I provide a reversible driving mechanism for the end- 30 less flight-chain which constitutes the conveyer and elevator.

With these ends in view my invention consists in the novel construction and arrangement of parts and in the combination of elements, which will be hereinafter fully 35 described and claimed.

To enable others to understand my invention, I have illustrated the preferred embodiment thereof in the accompanying drawings, 40 forming a part of this specification, and in which—

Figure 1 is a side elevation of a threshing-machine with my improved conveyer and elevating mechanism applied thereto and 45 adapted for service in connection with a measuring and bagging mechanism. Fig. 2 is a vertical cross-sectional view through the threshing-machine and my improved conveying and elevating mechanism to show the relation of the latter to the threshing-machine and its cleaning-shoe, the full lines representing a measuring and bagging mechanism ad-

justed for use in connection with the endless flight conveyer when driven in one direction and the dotted lines representing the position 55 of the measuring and bagging mechanism when the conveyer is run in the opposite direction. Fig. 3 is a detail perspective view of part of the endless conveying and elevating mechanism, and Fig. 4 is a detail view of 60 the reversible driving mechanism for impelling the endless flight-chains in either direction.

Like numerals of reference denote like and corresponding parts in each of the several 65 figures of the drawings.

To enable others skilled in the art to understand my invention, I have illustrated so much of the threshing-machine as is necessary to show my improved mechanism applied 70 thereto. The threshing-machine or grain-separator is represented by the numeral 1 and its cleaning-shoe by 2; but I would have it understood that I do not strictly confine myself to any particular type of threshing- 75 machine, as I am aware that the improvements may be used generally in connection with threshing-machines which employ cleaning-shoes for separating the grain from the chaff.

My improvements consist in a novel form or construction of endless-chain conveyer and elevator adapted for use in connection with a grain measuring and bagging mechanism. The casing for the endless flight-chains 85 is arranged to extend entirely around the machine-casing of the threshing-machine transversely across and outside of the same. The conveyer and elevator casing is designated in its entirety by the numeral 3, and 90 said conveyer-casing consists of the bottom section 4, the upright members 5 6, and the top section 7, all of which are continuous with each other to provide an inclosure for the endless flight-chains forming the conveyer 95 and elevator. The bottom section 4 of the conveyer-casing is curved or inclined longitudinally beneath the primary machine-casing for the purpose of taking up the slack in the endless flight-chains. The top section 7 100 of the conveyer-casing extends across the deck of the threshing-machine in a substantially horizontal direction, and said top section 7 is somewhat longer than the bottom

section 4 of the conveyer-casing, so that its ends project farther beyond the sides of the primary machine-casing than the ends of the bottom section 4. The upright members 5 6 5 of the conveyer-casing are inclined outwardly and upwardly from the bottom section 4 to the top section 7, substantially as shown by Fig. 2 of the drawings, and in arranging the flight-chains within the conveyer-casing the 10 upright legs or parts of said flight-chains are caused to conform to the inclination of the upright members 5 6 of the conveyer-casing and the flights thereon travel adjacent to the outer walls of said upright members 5 6, 15 whereby the flights are caused to discharge the grain to the measuring and bagging mechanism presently described. These upright members 5 6 of the conveyer-casing are each notched or otherwise formed at a point 20 intermediate of its height to provide an overhanging spout, the spout on one upright member 5 being indicated at 8 and the spout on the other upright member 6 being represented by the numeral 9. These spouts of 25 the upright members of the conveyer-casing open downwardly, and as the grain is carried up by the flights of the endless conveyer and elevator the grain is free to escape through one spout or the other 8 9, according to the 30 direction in which the conveyer and elevator is driven.

To support the endless flight-chains in proper position within the conveyer-casing 3, I provide a plurality of shafts, which are arranged at the several angles or corners of the conveyer-casing and lie transversely therein to properly receive and direct the endless flight-chains in their course through the conveyer-casing. The upper shafts 10 11 are 35 journaled in suitable bearings at opposite ends of the upper section 7 of the conveyer-casing, while the lower shafts 12 13 are arranged at the respective ends of the lower section 4 of said conveyer-casing. The upper shafts 10 11 are not in the same vertical plane as the lower shafts 12 13, and all of the shafts are provided with sprocket-wheels 14 to engage with the links of the endless flight-chains. 40

50 The endless conveyer and elevator is designated in its entirety by the numeral 15, and it consists of two strands or lengths of endless link chains 16 17 and cross-flights 18, suitably attached to the strands or lengths 55 16 17. The lengths or strands of endless chains 16 17 are held in parallel relation to each other by the pairs of sprocket-wheels 14 on the several shafts of the conveyer and elevator mechanism, and the flights 18 are attached to said parallel endless chains at suitable intervals from each other and extend outwardly from the chains. The links of the endless chains, to which the flights are attached, are provided with flat plates 19, which 60 65 are reinforced by the webs 20 to brace and sustain the flights 18, which are applied laterally on the plates 19 and are securely fas-

tened thereto—as, for example, by the rivets shown in Fig. 3.

In connection with the described construction of the casing and endless flight-chains which constitute the conveyer and elevator mechanism I employ a single measuring and bagging mechanism 21, which is adapted to be mounted detachably beneath either of the 70 75 spouts 8 or 9 of the conveyer-casing.

I do not desire in this application to claim any specific construction of the measuring and bagging mechanism, because such mechanism forms the subject-matter of a separate 80 application filed by me of even date herewith, Serial No. 663,304.

In the drawings I have illustrated in a general way a measuring and bagging mechanism suitable for use in connection with my 85 improved conveyer and elevator, and in this connection I desire to state that a single measuring and bagging mechanism is mounted detachably on the conveyer-casing, so that it may be adjusted beneath either of the 90 spouts 8 or 9, according as the attendant desires to employ such mechanism on one side or the other of the threshing-machine.

It will be understood that the threshing-machine may occupy such a position with relation to a barn or other structure that the measuring and bagging mechanism cannot be conveniently used on the side of the machine adjacent to the obstruction, and under these conditions of service it is highly desirable 100 that the bagging and measuring mechanism may be used on either side of the threshing-machine. To this end I construct the conveyer-casing with the independent spouts on the respective sides of the threshing-machine 105 and mount the measuring and bagging mechanism detachably on said conveyer-casing to enable it to be used on either side thereof. This casing 22 of the measuring and bagging mechanism is provided at its lower end with 110 the diverging delivery-spouts 23, to either or both of which may be attached a bag or bags 115 designed to receive the grain from the said casing 22, and I also provide fastenings 24 25 for detachably connecting said casing 22 to 120 the conveyer-casing 3. The fastenings may be of any suitable or preferred construction; but, as shown by the drawings, I employ the hooks and catch-plates adapted to be fastened to the conveyer-casing and to the casing 22 125 of the bagging and measuring mechanism. The endless conveyer and elevator is designed to be driven by connections with one of the shafts of the threshing-machine, and I provide a driving mechanism 26 for such conveyer and elevator. The shaft 27 of the conveyer and elevator driving mechanism is geared through the intermeshing beveled gears 28 29 to a sprocket-wheel shaft 10 within the conveyer-casing 3, and one end of said 130 shaft 27 protrudes beyond the side of the threshing-machine to receive a belt-pulley 30, around which is passed an endless driving-belt 31, leading to the pulley on one of the

shafts of said threshing-machine. This belt may be crossed between the pulley 30 and the driving-pulley of the threshing-machine for the purpose of impelling the endless conveyer 5 and elevator in one direction, or a straight belt may be used to drive the pulley 30 in the opposite direction when the endless conveyer and elevator is to be propelled in an opposite direction.

10 The driving-shaft 27, having the pulley and the interchangeable straight and crossed belts, constitutes in effect a reversible driving mechanism by which the endless conveyer may be driven in either direction to adapt it to discharge to the weighing and bagging mechanism, and thus the conveyer may be operated to discharge the grain in the spouts of the upright legs of the conveyer-casing without carrying the grain across the upper horizontal 15 length of the conveyer or the deck of the threshing-machine, thereby obviating any tendency of the straw or chaff to become caught in the upper sprocket-wheels or shafts of the conveyer and elevator.

20 One of the important features of my improvement is the outward inclination of the upright legs of the casing and the endless elevator and the arrangement of the flights on the elevator to sweep close to the outer sides 25 or walls of the conveyer-casing. This organization of the parts is advantageous in that provision is made for the quick and thorough discharge of the grain from the elevator-flights at the protruding spouts of the upright 30 legs of said casing, and the grain is delivered thoroughly and effectually from the elevator to the spouts and the weighing and bagging mechanism.

35 One of the important features of my improved conveyer and elevator mechanism is that it occupies an exceedingly compact relation to the casing of the threshing-machine, and it lies wholly within the vertical plane of the carrying-wheels of said threshing-machine, so that the conveyer and elevator mechanism does not project beyond the threshing-machine to offer obstruction to the passage of such machine through gateways and narrow 40 places, thus overcoming one of the objections 45 to ordinary elevators on threshing-machines.

50 Another important feature of my improvement is that the lower section 4 of the conveyer-casing and the lower strand of the bucket conveyer lies directly beneath the 55 delivery end of the cleaning-shoe 2 of such threshing-machine, and thus the cleaned grain from the shoe 2 is delivered directly to the conveyer for the purpose of being carried from the shoe directly to the measuring and 60 bagging mechanism 21, whereby intermediate screw conveyers or other analogous devices to transfer the grain from the shoe to a discharge-conveyer are wholly obviated.

65 The operation may be described, briefly, as follows: The measuring and bagging mechanism is attached to the conveyer-casing in close relation to and beneath one or the other

of the overhanging spouts 8 or 9 thereof, and the endless flight-chains are driven by the driving mechanism 26 in a direction to carry 70 the grain up to such spout 8 or 9. As the grain is discharged from the shoe 2 it passes directly to the section 4 of the conveyer-casing and is deposited in the path of the flights of the endless conveyer and elevator, the latter serving to carry the grain up and along one of the upright members 5 or 6 of the conveyer-casing and to deposit the same into the spouts 8 or 9, from whence the grain passes directly into the measuring and bagging 80 mechanism.

If it is desired to employ the measuring and bagging mechanism on the opposite side of the machine, it is only necessary for the operator to detach the casing 22 and transfer it 85 bodily to the other side of the machine, after which the casing 22 is attached to the conveyer-casing beneath the other spout thereon. The driving mechanism 26 is now adjusted to impel the conveyer and elevator in the opposite direction, and the operation of moving the grain from the shoe to the last-named delivery-spout is precisely the same as heretofore described.

90 It will be observed that my improved conveyer and elevator mechanism does not carry the grain up to the upper section 7 of the conveyer-casing nor across the deck of the primary machine; but, on the contrary, the grain is carried up one upright member of 100 the conveyer-casing as far as the delivery-spout thereon, at which point the grain is discharged from the flights directly into the delivery-spout and thence to the measuring and bagging mechanism. This discharge of 105 the grain to the delivery-spout at an intermediate point of the height of the conveyer-casing is thoroughly effected by reason of the outward inclination given to the upright members of the conveyer-casing and the traveling conveyer and elevator, and I thus avoid 110 the liability of clogging of the sprocket-wheels and shafts 10 11 by straw and chaff, which would become caught in said sprocket-wheels and shafts if the grain was carried across the 115 deck of the threshing-machine by the operation of the endless conveyer and elevator.

Having thus described my invention, what I claim as new, and desire to secure by Letters Patent, is—

120 1. The combination of an elevator-casing adapted to extend around a threshing-machine in the vertical plane of the cleaning-shoe thereof and having its legs inclined upwardly and outwardly from the lower horizontal length of said casing, the guide wheels or pulleys situated at the corners of the casing, delivery-spouts on the inclined legs of the casing at points below the upper guide wheels or pulleys, and formed by notches or 125 breaks in the outer walls of the inclined legs, and an endless conveyer fitted to the guide wheels or pulleys and having the flights arranged to sweep close to the outer walls of 130

the inclined casing-legs and across the notches or breaks and adapted to dump automatically when the conveyer-flights reach the notches or breaks, whereby the grain on said elevator-flights is effectively discharged into the delivery-spouts, substantially as described.

2. The combination of an elevator-casing having the inclined legs between its short and long horizontal lengths, a shaft, 10, at one ¹⁰ upper corner of the casing and having a guide-wheel, another shaft, 11, carrying a guide-wheel and arranged at the opposite upper corner of said casing, the shafts, 12, 13, carrying other guide-wheels and located at ¹⁵ the lower corners of the casing and in positions within the vertical planes of the upper guide-wheels, a driving-shaft geared to the shaft, 10, and adapted to be driven in either

direction by power connections with a threshing-machine, the delivery-spouts situated on ²⁰ the inclined legs of the casing below the upper guide-wheels, and the endless elevator fitted to the guide-wheels and having its flights arranged to sweep close to the outer inclined walls of the casing-legs and to assume transversely-inclined positions toward the delivery-spouts, whereby automatic dumping is effected, substantially as set forth.

In testimony that I claim the foregoing as my own I have hereto affixed my signature in ²⁵ the presence of two witnesses.

FRANK DENTLER.
